TUYÈRE

Alfred J. Ebner and Owen R. Rice, Chicago, Ill.,
assignors to Freyn Engineering Company, Chi-
cago, Ill., a corporation of Maine

Application January 29, 1934, Serial No. 708,784

8 Claims. (Cl. 122—6.6)

The present invention relates to improvements in tuyères.

More particularly the present invention relates to improvements in the cooling features of tuyères such as are used in blast furnaces. Tuyères for this purpose are commonly made of copper, because of the high heat conductivity of that metal. Inasmuch as such tuyères are subjected to very high temperatures, it has been common practice to cool them with water, a current of water being directed through the tuyère wall.

It has been suggested that a coil made of a material having a higher melting point than that of the tuyère body be cast within the material of the tuyère around the nose end thereof for the positive local circulation of a cooling fluid to withstand the high temperatures present in blast furnaces, but a homogeneous unification of such a coil with the material of the tuyère body has not been commercially feasible. It has also been suggested to cast a bent tube within the nose portion of a cast iron tuyère, but this suggestion has not proved successful, for the reason, among others, that it did not provide a water jacket within the wall of the tuyère, which water jacket has proven to be desirable in commercial service. It has also been suggested to core out a hole in the nose portion of the tuyère in the casting operation by which the tuyère is made, but this suggestion has not proven successful for the reason that the cored out hole in the nose of the tuyère is inaccessible and it has not been possible to completely remove the core sand. Particles of sand clinging to the wall of the cored out space seriously interfere with the heat conducting function of the cooling medium by promoting the existence of stagnant films of fluid in and about the particles of core sand and interfering mechanically with and stagnating the flow of the cooling medium. The particles also form anchorages for bubbles of steam which tend to form when molten iron comes in contact with the tuyère nose, and these bubbles of steam form an insulating medium between the heated copper and the water which is intended to cool it, to the consequent detriment of the copper.

An object of the present invention is to avoid the difficulties above referred to and to provide a water-cooled tuyère having means for positively conducting cooling medium into and through the nose wall of the tuyère, which tuyère, will be free from stagnant spaces and less effective heat conducting media, such as metallic scale, etc.,

and will have perfectly smooth surfaces for the passage of the cooling medium.

A further object is to provide an improved tuyère having a water jacket in the wall thereof and having a pipe extending around the nose of the tuyère within the material of said nose, which pipe is so perfectly bonded and merged with such physical homogeneity with the material of said tuyère as to constitute an unimpaired and uniformly good heat conducting medium between the outer surface of the tuyère nose and the cooling water in the pipe. 5

A further object is to provide an improved water-cooled tuyère which is well adapted to meet the needs of commercial service. 15

Further objects will appear as the description proceeds.

Referring to the drawing—

Figure 1 is a view in end elevation showing the butt end of a tuyère embodying the principles 20 of the present invention;

Figure 2 is a longitudinal sectional view taken along the plane indicated by the arrows 2—2 of Figure 1; and

Figure 3 is a view in end elevation looking toward the nose end of the tuyère illustrated in the preceding figures. 25

The numeral 10 indicates a tuyère, the outer contour of which may follow standard practice. The butt end of said tuyère may be provided with 30 a frusto-conical portion 11 adapted to seat within the usual cooler (not illustrated). The nose end of the tuyère 10 is indicated by the numeral 12. Extending from the butt end to the nose end of the tuyère is an outer wall 13 and an inner wall 14, providing between them the annular space 15 which, in operation, will be filled with water. At the butt end of the tuyère is an inlet aperture 16, the connection to which will be described presently. Also disposed at the butt end 40 is an outlet aperture 17 for cooling water, which aperture 17 communicates directly with the water space 15. 35

Cast within the nose end 12 is a length of copper pipe indicated by the numeral 18, which pipe, as shown in Figure 3, extends circumferentially of the tuyère through almost a complete circle. Said length of pipe 18 also includes the longitudinally extending portion 19 communicating with the inlet aperture 16. The other 50 end of the length of pipe 18 communicates with the annular water space 15. Said other end of the length of pipe 18 is indicated by the numeral 20. 45

According to the present invention, the pipe 55

18 will have substantially the same melting point as the material of the tuyère 10. In the case of a copper tuyère, which material is at present preferred, the pipe 18 will preferably be a drawn 5 copper tube having a smooth inner wall. It is essential in achieving the objects of the present invention that in the casting operation in the manufacture of the tuyère the molten copper or other material of the tuyère will form a perfect 10 bond with the material of the pipe 18, making a homogeneous combination of the material of the tuyère 10 with the material of the pipe 18. If it is preferred to choose a material for the pipe 18 different from the material of the tuyère 15 10, the two materials should be so chosen that in the casting operation of the tuyère a complete alloy or combination of the tuyère 10 and the pipe 18 will be accomplished. Moreover, the coefficient of expansion of the material of 20 the pipe 18 should be substantially the same as the coefficient of expansion of the tuyère 10, thereby eliminating the undesirable tendency to sever the close bond between the pipe 18 and the tuyère material, which might occur if said 25 pipe 18 and tuyère 10 were composed of materials having different coefficients of expansion.

As indicated above, it is preferred to use a drawn copper tube for the pipe 18 about which the material of the tuyère is poured in the casting 30 operation in the manufacture of the tuyère, whereby a perfect bond is accomplished between the outer wall of the pipe 18 and the material of the tuyère, leaving no dead spaces and less effective heat conducting media and avoiding 35 difficulties due to different coefficients of expansion of the material of the pipe 18 and of the tuyère 10. By reason of the fact that the pipe 18 is a drawn copper tube, it will have a smooth inner wall, offering no mechanical ob- 40 structions to promote the existence of stagnant films of fluid or interfering with the flow of the cooling medium or to form anchorages for bubbles of steam. The drawn copper tube of commerce has a heat conductivity at least equal to 45 the heat conductivity of cast copper, and as a result the heat conductivity of the tuyère is at least as great as though the tuyère were formed of all-cast copper.

In operation, cooling water will be supplied 50 to the length of pipe 18 through the inlet aperture 16. This cooling water will flow throughout the length of the pipe 18 positively cooling the nose end 12. The water from said pipe 18 will be discharged through the outlet end thereof 55 into the water space 15, circulating through said water space 15 out of the outlet aperture 17. At the same time the entire water space 15 of the tuyère is filled with water as in prior practice.

60 Though a preferred embodiment of the present invention has been described in detail, many modifications will occur to those skilled in the art. It is intended to cover all such modifications that fall within the scope of the appended 65 claims.

What is claimed is—

1. A tuyère having spaced circumferential walls for providing a water space, said tuyère also having a nose portion, and a length of pipe 70 within said tuyère, said length of pipe having a circular portion embedded within said nose portion and homogeneously united with said nose portion, one end of said length of pipe communicating with said water space, the other 75 end of said length of pipe communicating with

the exterior of said tuyère, said water space also having communication with the exterior of said tuyère, said length of pipe being of a material having substantially the same melting point and at least as high heat conductivity as the mate- 5 rial of said nose portion.

2. In a tuyère, in combination, a pair of spaced circumferential walls providing a water space, and a nose portion, said nose portion having a length of pipe cast therein and homogeneously united therewith, one extremity of said pipe communicating with said water space, said tuyère having an outlet aperture communicating with said water space, and an inlet aperture communicating with the other end of said pipe, 10 said pipe being a drawn tubing of a material having substantially the same melting point and at least as high heat conductivity as the mate- 15 rial of said nose portion.

3. In a tuyère, in combination, a wall portion, 20 and a nose portion, said nose portion having a circular smooth bored tube cast therein and homogeneously united therewith, means for admitting cooling medium to one end of said tube, said tuyère having a water spacer communicat- 25 ing with the other end of said tube, said water space having communication with the exterior of said tuyère, said tube being of a material having substantially the same melting point and at least as high heat conductivity as the material 30 of said nose portion.

4. A tuyère comprising, in combination, a pair of circumferential walls providing a water space, and a nose portion, said nose portion having cast 35 therein and homogeneously united therewith a drawn tube extending circumferentially of said nose portion, means for admitting cooling water to one end of said tube, said tube communicat- 40 ing with said water space, said tuyère having an outlet aperture for discharging water from said water space, said tube being of a material having substantially the same melting point and at least as high heat conductivity as the material of 45 said nose portion.

5. In a tuyère, in combination, a pair of spaced 45 walls providing a water space, and a nose portion, a length of pipe having a portion of substantially circumferential contour, said portion of said circumferential contour being cast within 50 said nose portion and homogeneously united therewith, one extremity of said length of pipe extending through said water space and communicating with the exterior of said tuyère, the other extremity of said length of pipe communicat- 55 ing with said water space, said tuyère having an aperture permitting communication between said water space and the exterior of said tuyère, said pipe being of a material having substantially the same melting point and at least as high heat conductivity as the material of 60 said tuyère.

6. In a tuyère, in combination, a wall portion and a nose portion, said nose portion having a circular smooth bored tube cast therein and homogeneously united therewith, and means for admitting cooling medium to one end of said tube, said tuyère having a water space communicat- 65 ing with the other end of said tube, said water space having communication with the exterior of said tuyère, said tube and said nose portion both being composed of copper.

7. In a tuyère, in combination, a wall portion and a nose portion, said nose portion having a circular smooth bored tube cast therein and homogeneously united therewith, and means for admitting cooling medium to one end of said 75

5 tube, said tuyère having a water space communicating with the other end of said tube, said water space having communication with the exterior of said tuyère, said tube having a heat conductivity at least equal to the heat conductivity of the material of said nose portion.

10 8. In a copper tuyère, in combination, a wall portion and a nose portion, said nose portion having a circular smooth bored copper tube cast therein and homogeneously united therewith, and

means for admitting cooling medium to one end of said tube, said tuyère having a water space communicating with the other end of said tube, said water space having communication with the exterior of said tuyère, said copper tube having 5 a heat conductivity at least equal to the heat conductivity of the material of said nose portion.
